his Attorney

UNITED STATES PATENT OFFICE.

WILLIAM U. GRIFFITHS, OF PHILADELPHIA, PENNSYLVANIA.

SAFETY DEVICE FOR OPERATING FLUSH-TANK VALVES.

1,343,261.

Specification of Letters Patent. Patented June 15, 1920.

Application filed October 21, 1918. Serial No. 259,095.

To all whom it may concern:

Be it known that I, WILLIAM U. GRIFFITHS, a citizen of the United States, and a resident of Philadelphia, in the county of Philadelphia and State of Pennsylvania, have invented an Improvement in Safety Devices for Operating Flush-Tank Valves, of which the following is a specification.

In institutions of various kinds housing 10 a greater or less number of people, particularly jails and other penal institutions, great trouble has been encountered in keeping the toilet apparatus in proper repair, particularly the flush apparatus.

15 The object of my invention is to provide a device adapted for operating the flush valve of a water closet flush tank, or a tank for similar purpose which is so situated as to be protected from the inmates of the jail 20 or other institutions.

A further object of my invention is to provide a device for operating the flush or other valve of a flush tank which is situated outside of a room or inclosure in which the 25 water closet bowl is situated, which device is provided with means extending into the said inclosure whereby the said device may be operated.

Although my invention is designed particularly for use in jails, penal institutions 30 and other places where relatively large bodies may be congregated, it will be understood that the same also is well adapted for use in private houses and other establishments of a more or less public character 35 but at which large gatherings are not in the habit of being congregated.

In order that my invention may be more readily and clearly understood and its practical 40 advantages fully and clearly comprehended and appreciated, reference may be had to the accompanying drawing in which I have illustrated one form of a convenient embodiment of apparatus constructed in accordance with my invention. It will be understood, however, that my invention is 45 adapted to be embodied in widely varying constructions which fall within the scope of the claims hereunto appended.

50 In the drawing:

Figure 1 is a top plan view of a device embodying my invention, a link of a chain extending therefrom to a valve or similar device to be operated, being shown in section, and a portion of a wall upon which

the device is supported, being also shown in horizontal section, and

Fig. 2 is a view partly in side elevation and partly in longitudinal section of the device shown in Fig. 1, a portion of the wall 60 supporting the said device being shown in vertical section.

Referring to the drawing: 1 designates a wall to which the device embodying my invention is secured and upon which it is 65 supported. Although the wall 1 is shown as consisting of a relatively thin sheet of material, it will be understood that the same may be of any greater thickness desired, as for instance, a brick, stone or concrete wall 70 or a wall of wooden frame structure.

2 designates a screw threaded tubular lug like member provided with a relatively wide flange 3 upon its inner end which is adapted to rest against the inner surface of the wall 75 1 about an opening 4 through the said wall and through which the screw threaded tubular member extends. In order to securely fasten the screw threaded tubular member 2 to the wall 1, I have provided a clamping nut 5 which has screw threaded engagement with the said member 2 and is adapted to be screwed and clamped firmly against the outer or rear side of the wall 1 so as to clamp the latter firmly between the flange 3 80 and the said clamping nut 5.

At its rear end the tubular supporting lug or projection 2 has screw threaded engagement with a sleeve 6, the latter being secured against accidental turning upon the 90 said lug or projection by means of a binding screw 7. The said sleeve 6 is provided with an upwardly extending arm 10 which is forked or bifurcated at its upper end 95 to form the oppositely disposed portions 11. 12 designates a lever which is pivoted intermediate the portions 11 upon a pivot bolt 14. The forward end of the said lever 12 has connection with the lower end of a chain 17 or other connection, the upper end of which has connection with a valve or other member to be operated. The rear end portion of the lever 12 to the left of the pivot 14 is provided with an adjustable weight 20 which is adapted to be secured in adjusted 100 position upon the rear end portion of the said lever by means of a binding screw 21. The said weight is provided at its forward end or side with a depending arm 22 which is adapted to contact with the rear end of 110

an operating bolt or bar 25 which is slidably supported in the tubular member 2 and also in an opening or hole through the rear end portion of the sleeve 6, which opening is in alignment with the opening through the tubular member 2. The rear end of the operating bolt or bar is provided with a flange 26 which gives a relatively wide contact bearing for the lower end of the contact 10 arm 22.

The forward end of the operating bolt or bar 25 projects beyond the front end of the tubular member 2 into the inclosure or room so that it may be pushed rearwardly by anyone from the inside of such inclosure or room. The rearward movement caused by such pushing causes rearward swinging movement of the arm 22 with a consequent upward swinging movement of the rear portion 20 of the lever 12. The front end portion of the said lever is thereby depressed so as to cause a downward movement of the chain or other connection 17 for operating a valve or similar device to which the said chain or other connection may be connected. The positions of the bolt or bar 25, the lever 12 and the weight 20 and arm 22 carried thereby, are clearly indicated in the dash and dot lines in Fig. 2 of the drawing.

30 In the construction as shown, the arm 22 is formed integrally with the weight 20. It is clear, however, that such integral arrangement is unnecessary and that the arm may be a separate member from the weight, the 35 said arm and weight being separately and independently secured to the rear end portion of the lever 12.

It is clear from the drawing and from the 40 foregoing description of the constitution that by reason of the projecting front or forward end portion of the bolt or bar 25, that the latter device may be operated from the inside of a room or inclosure and that the party operating the same is excluded or 45 prevented from having access to any portion of the means for flushing a water closet bowl or other similar member which could be put out of order by such person. The only thing that a person situated within such a room or inclosure can do is to either push or pull upon the operating bolt or bar 25.

I claim:

1. In combination, a wall, a bracket supported in rear of said wall, said bracket having an opening extending through a portion thereof, an opening through said wall, a slidable bar situated in said opening and projecting beyond the front of the said wall, a lever pivoted upon said bracket and means having connection with said lever and contacting with the rear end of said bar whereby sliding movements of the latter cause pivotal movements of said lever.

65 2. In combination, a wall having an open-

ing therethrough, a tubular member extending through said opening, said member having a lateral flange resting against the portion of wall surrounding the said opening, means for engaging the said tubular member upon the opposite side of said wall from said flange for clamping the wall against said flange, an arm having connection with the rear end of said tubular member, a lever pivoted intermediate its ends to said arm, 75 the forward end of said lever having connection with a device to be operated, an arm secured to the opposite portion of said lever, said arm extending away from said lever, and means slidably supported in said 80 tubular member, the front end of which projects beyond the front face of said wall and the rear end of which extends beyond the said tubular member and contacts with the end of said last mentioned arm, whereby movement of said means actuates the 85 said arm and the said lever.

3. In a device for operating a valve of a flush tank, said device being situated outside an inclosure while the part to be flushed is situated inside said inclosure, the combination of a pivoted lever, means for operatively connecting the said lever with a valve of a flushing apparatus, means for supporting said lever and a slidably supported bar extending through an opening in a wall of said inclosure, one end of said bar projecting into the interior of said inclosure and the other outer end contacting with said lever to operate the same.

4. In a device for operating a valve of a flush tank, said device being situated outside an inclosure while the part to be flushed is situated inside said inclosure, the combination of a bracket situated externally of a wall of the said inclosure, said bracket having an opening communicating with the interior of said inclosure, a slidable member situated in the said opening, the front end of which projects into the said inclosure and the rear end of which projects beyond the said bracket, a lever pivoted intermediate its ends upon the said bracket, means connecting the forward end of said lever with the valve to be operated, 110 a weight upon the opposite end of said lever and a depending arm extending from said lever and contacting with the rear end of the said slidable member.

5. In a device for actuating a valve of a flush tank, the said device being situated outside of one of the walls of an inclosure while the part to be flushed is situated inside the said inclosure, said device comprising a tubular member extending from the interior of said inclosure to the exterior thereof, means for securing the said tubular member to the wall through which it projects, an upwardly extending arm secured to the rear end of said tubular member, a 130

lever pivoted intermediate its ends to the upper end of said arm, said lever extending in a direction transversely of the said wall, means connecting the front end of said lever with the valve to be operated, a weight secured upon the opposite end of said lever, said weight holding the rear end of said lever in its lowermost position, an arm integral with said weight and depending there-

from and a slidable member situated in 10 the said tubular member, the front end of which projects into the said inclosure, while the rear end of which contacts with the said depending arm.

In testimony that I claim the foregoing 15 as my invention I have hereunto set my hand this 20th day of September, A. D., 1918.

WILLIAM U. GRIFFITHS.
